UNITED STATES PATENT OFFICE.

MARION W. PITNER, OF CHICAGO, ILLINOIS.

LAMP.

970,948.

Specification of Letters Patent. Patented Sept. 20, 1910.

Application filed June 11, 1907. Serial No. 378,403.

To all whom it may concern:

Be it known that I, MARION W. PITNER, a citizen of the United States, residing at Chicago, in the county of Cook and State of Illinois, have invented new and useful Improvements in Lamps, of which the following is a specification.

The invention relates to an improvement in lamps of the vapor burning type, comprehending specifically a construction whereby the lamp is rendered self-generating and the vaporization controlled directly by and in proportion to the heat from the burners.

The main object of the present invention is the provision of a generator disposed within the heat zone from the burners and adapted to receive the fuel vaporizing heat directly from the burners, the disposition of the generator and feed conduit leading thereto insuring an even and constant flow of the fuel and a steady generation of gas in sufficient quantity to properly supply the burners.

Another object of the invention is the provision of a feed conduit leading to and in communication with the generator, and the disposition of this conduit within the heat zone from the burners, so that the fuel is initially heated during its passage through the conduit and prior to its entrance into the generator, whereby the vaporization within the generator is materially facilitated and a more uniform gas supply maintained.

Another object of the invention is to materially simplify the construction and arrangement of the lamp parts, whereby to provide for the convenient and ready assembly or separation of said parts when desired, and thus insure convenient accessibility of the material parts of the lamp when replacement or repair is necessary.

With these and other material objects in view, the invention consists in certain details of construction which will be fully described in the following specification, reference being had therein particularly to the accompanying drawings, in which:—

Figure 1 is a vertical sectional view, partly in elevation, of a lamp constructed in accordance with my invention. Fig. 2 is a transverse section of the same on line 2—2 of Fig. 1. Fig. 3 is a vertical sectional view partly in elevation illustrating the connection of the supply pipe and feed tube. Fig. 4 is a bottom plan of the delivery end of one of the

burner tubes. Fig. 5 is a vertical section of the grid for the burner tube. Fig. 6 is a perspective view of the coupling for connecting the hanger tube and burner ring or spider. Fig. 7 is a plan of the globe supporting ring. Fig. 8 is an elevation of the body casting of the lamp. Fig. 9 is a horizontal section partly in elevation illustrating the connection between the generator and valve body. Fig. 10 is a modified form of the body casting.

Referring particularly to the accompanying drawings, 1 represents the hanger tube which may be of any desired length and is preferably adapted for engagement at the upper end with any desired form of ceiling plate. To the lower end of the hanger tube is secured through an exterior threaded connection a coupling 2, preferably of the ordinary sleeve type and formed with a longitudinally disposed slot 3, opening through the upper end of the coupling and terminating above the lower end thereof, as clearly shown in Fig. 6.

A connecting plug 4 is secured in the lower end of the coupling 2, preferably through the usual threaded connection, the relatively lower end of the plug projecting below the coupling and being adapted to receive the spider 5. The spider is in the form of a cylindrical body provided with one or more tubes 6 radiating from said body and in open communication with the interior thereof. In the present instance I have shown the tubes 6 arranged in cluster form and six in number, though it is to be understood that such arrangement is not essentially material to the present invention, as I contemplate the use of one or any number of burner tubes. The relatively outer or free end of each tube 6 is bent or formed to provide a depending outlet, which is interiorly threaded at 7 for the reception of a burner tube 8.

The burner tubes 8 are of frusto-conical formation in longitudinal section, being interiorly formed, however, with a longitudinally extending bore 9 of even diameter throughout. The frusto-conical formation of the burner tube tends to materially thicken the relatively lower portion of the wall thereof, for a purpose which will presently appear. At the relatively lower end the bore 9 of the burner tube is increased in diameter to form a chamber 10, the lower portion of the wall of which is threaded at 11.

12 represents a grid comprising a cylindrical disk of metal of appropriate thickness, the peripheral edge of which is threaded for engagement with the threads 11 of 5 the chamber 10 of the burner tube. The grid 12 comprises essentially a centrally disposed solid section 13 extending diametrically of the plug, from which section extend in both directions a series of parallel slots 14 opening through the peripheral edge of the disk. While preferring the parallel disposition of the slots 14, it is to be understood that they may have any angular arrangement relative to the central section 15 desired, the sole requirement being that the slots open entirely through the body of the disk.

The lower end of the burner tube is exteriorly beaded at 15 to provide for the convenient application of a mantle 16, which in ordinary use is adapted to be secured by a suitable connection about the burner tube 20 above the bead.

The relatively lower end of the spider body is interiorly threaded for the reception of the upper end of a mixing tube 17, comprising a length of tubing terminating above the lower ends of the burner tubes. The lower end of the mixing tube is connected directly to a casting 18, hereinafter termed the body of the lamp. The casting comprises a hollow sphere 19 from which depend arms 20 arranged in spaced parallel relation. The lower ends of the arms 20 35 are integrally connected with a hollow sleeve-like section 21, which is thus disposed below the sphere 19. The sphere is formed in the relatively upper portion with a threaded opening 22 for the reception of the lower end of the mixing tube, and in alignment with the opening 22, at a diametrically opposite point with a second opening 23, for a purpose which will presently appear. Intermediate the openings 22 and 23 the 40 wall of the sphere is formed with a series of circumferentially or otherwise disposed openings 24 in which are secured one or more air supply tubes 25. The tubes 25 thus radiate from the sphere, and may be prolonged the desired distance to carry their open free ends beyond the plane of the burner tubes to insure a proper supply of oxygen to the sphere.

A globe holder support 26 is threaded into the section 21 of the body, said support being of tube like form and depending below the section 21 the distance requisite to properly support the globe ring 27, which ring or holder, more clearly shown in Fig. 60 7, comprises a sleeve 28, of a size to encircle the support 26, and interrupted or open at 65 29 for a purpose hereinafter described. The sleeve 28 is provided with a set screw 30, whereby the sleeve may be held in adjusted position on the support, said sleeve

being further provided with radiating arms 31 supporting at their outer ends a ring 32, surrounding the sleeve 28, and of sectional formation to receive and engage the lower edge of the globe. An ornamental band 33 70 is arranged to support the upper end of the globe, said band being secured upon the ends of the air supply tubes 25 through the medium of flanged hollow plugs 34 threaded in the ends of the tubes, as clearly shown 75 in Fig. 1.

The feed conduit of the lamp proper comprises a section of pipe 35 within which is loosely disposed a feed tube 36, having a comparatively restricted bore. Between the 80 pipe 35 and the tube 36 is disposed a layer of asbestos 37 or other non-conducting material, the function of which is to prevent vaporization of the fuel passing through the feed tube 36, while admitting, however, the 85 passage of sufficient heat from the burners to initially heat the fuel to a degree below vaporizing point.

The feed conduit is secured in the burner in the following manner. The upper end 90 of the conduit is disposed within the hanger tube 1, and below the lower end of said tube is projected laterally through the slot 3 in the sleeve coupling 2. The conduit is then passed down between two of the spider tubes 95 6, past the sphere 19 and then laterally between the arms 20 of the body, through the sleeve section 21 thereof and downwardly through the globe holder support 26, depending below the lower end of the latter, 100 as shown in Fig. 1.

The nonconducting lining 37 and the feed tube 36 terminate above the lower end of the feed pipe 35, the latter below the feed tube being interiorly threaded for the reception of a valve body 38, the upper end of which is reduced in the form of a plug for insertion within the feed tube. The valve body is formed with the usual longitudinally extending duct 39, which receives the fuel 110 from the feed tube 36, said body being also provided with a cut-off valve 40 suitably mounted for movement in the body and having its stem projected beyond the body and formed or provided for manual operation.

The valve body is provided with a laterally projecting arm 41 interiorly formed with a channel in communication with the duct 39 of the body, said channel 42 being at the free end of the arm 41 turned upwardly, as at 43, and opening through the upper surface of the arm, the portion 43 of the channel being preferably slightly flaring at the mouth.

The generator comprises an appropriate length of pipe 44, the relatively lower end of which is adapted for connection with the arm 43 of the valve body. In this connection I have provided a means for attaching the generator in place to provide for the 125 130

proper passage of the gasoline, while at the same time permitting the practically instantaneous disconnection of the generator from the valve body when desired. In providing this connection I secure in the lower portion of the generator a union plug 45, formed with an axial bore to permit passage of the gasoline. The relatively lower portion of the plug is exteriorly threaded, 10 while the extreme lower end of the plug is of conical formation, as shown. A locking ring 46 is secured upon the threaded lower portion of the plug and is of such diameter as, in the position noted, to encircle the arm 41. Diametrically opposite the connection of the ring 46 with the plug 45 said ring is formed with a threaded opening 47 to receive a threaded push rod 48, the lower end of which is provided with a thumb piece 49 20 for convenient operation.

In connecting the generator to the valve body the push rod 48 is withdrawn the desired distance and the ring 46 is passed over the end of the arm 41 until the conical end 25 of the plug 45 approximately registers with the mouth of the channel 43. The rod 48 is then threaded through the opening 47 until it contacts with the lower surface of the arm 41, the movement of the rod being continued until the conical end of the plug 30 45 is seated in the flared mouth of the channel section 43. The lower end of the generator is thus secured in a fluid tight manner to the arm of the valve body, the connection 35 providing, however, for practically instantaneous separation of the parts when desired by withdrawing the rod 48 and lifting upward on the ring 46 to remove the end of the plug from the channel in the arm.

40 The generator extends above the arm 41 in practically parallel relation with the globe holder support 26, being above the sleeve section 21 of the body projected laterally to a slight degree until disposed between the arms 20 of the body, the extreme upper end of the generator being passed through the opening 23 in the sphere 19 and provided with a plug 50 having a restricted outlet 51. As the generator seats 45 loosely in the opening 23, it is obvious that disconnection of said generator from the arm 41, in the manner previously described, permits the complete removal of the generator in a simple and expeditious manner.

50 The generator is preferably disposed on the side of the body opposite the feed pipe 35, thereby avoiding interference and providing for the convenient connection of both of these parts with the body.

55 The lamp is supplied with fuel through a supply pipe 52, preferably in the form of a wire tube having a comparatively restricted bore. The supply pipe 52 extends within the hanger tube 1 and is connected to the upper end of the feed pipe in the

manner shown in Fig. 3. For this purpose the upper end of the feed pipe is interiorly threaded to receive the lower end of a coupling 53, the interior bore 54 of which is slightly flared at the upper end, as at 55. 70 The upper end of the coupling is exteriorly threaded to receive a lock nut 56, and the lower end of the supply pipe 52 is provided with a jamb 57 to fit within the flaring end of the bore 54. With the jamb 57 fitting 75 in the bore of the coupling the nut 56 may be applied to firmly fix the jamb in the mouth of the bore, thereby providing a fuel tight connection which may be readily operated to permit separation of the parts 80 when desired.

With the parts constructed and assembled as described it will be understood that the fuel, as gasoline or the like, will find its way through the feed tube 36 of the feed 85 conduit past the valve 40 and into the generator 44. During the travel of the fuel through the feed conduit it is to be noted that it will receive the heat from the burners of the lamp, so that said fuel is highly 90 heated during its travel through this conduit. By virtue of the asbestos lining, however, the fuel is protected against that degree of heat necessary to vaporize the fuel, it being desirable that the fuel be delivered 95 to the generator in a liquid state. As the fuel reaches the generator it is subjected to the heat of this body and vaporized, passing through the outlet port 51 and into the 100 sphere 19, the vacuum produced by the travel of the vapor tending to draw air through the tubes 25 to be mixed with the vapor for ignition purposes. Owing to the opposing paths of travel of the vapor and air a complete mixture occurs in the mixing 105 tube 17, from which the mixture passes to the burners and is ignited. The pressure of the gas tends to distend the mantles 16 into proper form, so that the resultant incandescence produces a brilliant and steady 110 light.

It will be noted that the generator 44, as well as the feed conduit is disposed within the heat zone of the burners, so that during the use of the lamp the generator is maintained at a sufficient degree of heat to completely vaporize the fuel admitted thereto, and avoid any flooding through improper vaporization.

In Fig. 10 I have shown a modified form 120 of body casting, wherein the section 21' is projected laterally so that the same is disposed out of alignment with the sphere 19'. By this means both the feed conduit 35' and the generator 44' may be carried through the lamp section without requiring the lateral bending of such parts as illustrated in the preferred form.

While preferring the detailed structure 130 herein described, it is obvious that various

changes and modifications may be resorted to without departing from my invention, and it is to be understood that I consider as within the spirit of the present invention all such changes and modifications as may fall within the scope of the appended claims.

Having thus described the invention what is claimed as new, is:—

- 10 1. A lamp including a hanger tube, a coupling having connection with said tube, a spider removably connected to the coupling, a series of burner tubes carried by the spider, a feed conduit extending through the hanger tube, said conduit being laterally projected through an opening formed in the coupling and depending between the burner tubes, and means for delivering the fuel from said conduit to the burner tubes.
- 15 2. A lamp including a hanger tube, a coupling having connection with the tube, a series of burners supported by the coupling, a feed conduit extending through the hanger tube and projected laterally through an opening in the coupling above the burners, said conduit depending between the burners and terminating below the same in alignment with the hanger tube, and means for delivering the fuel from the conduit to the burners.
- 20 3. A lamp including a hanger tube, a coupling connected with the tube and formed with an opening, a spider arranged below the coupling, a plug connecting the coupling and spider, a series of burner tubes carried by the spider, a mixer connected to the spider and depending in alignment with the hanger tube, a feed conduit extending through the hanger tube and projected laterally through the opening in the coupling, said conduit depending between the burners in parallel relation to but beyond the mixer, and means for delivering the fuel from said conduit to the burner tubes.
- 25 4. A lamp including a hanger tube, a coupling connected with the tube and formed
- 30 with an opening, a spider arranged below the coupling, a plug connecting the coupling and spider, a series of burner tubes carried by the spider, a mixer connected to the spider and depending in alignment with the hanger tube, a feed conduit extending through the hanger tube and projected laterally through the opening in the coupling, said conduit depending between the burners in parallel relation to but beyond the mixer, and a generator supported solely by the conduit and in communication with the mixer.
- 35 5. A lamp including a hanger tube, a globe holder support arranged below and in alignment with the hanger tube, a burner carrying spider arranged between and in alignment with the hanger tube and globe holder support, a mixer arranged between and in alignment with the globe holder support and spider, a feed conduit arranged within the hanger tube and globe holder support, said conduit being arranged wholly beyond the spider and mixer, and means for delivering the fuel from the conduit to the mixer.
- 40 6. A lamp including a hanger tube, a globe holder support arranged below and in alignment with the hanger tube, a burner carrying spider arranged between and in alignment with the hanger tube and globe holder support, a mixer arranged between and in alignment with the globe holder support and spider, a feed conduit arranged within the hanger tube and globe holder support, said conduit being arranged wholly beyond the spider and mixer, and a generator supported by the conduit and in communication with the mixer, said generator being extended lengthwise the globe holder support but beyond the same.
- 45 In testimony whereof, I affix my signature in presence of two witnesses.

MARION W. PITNER.
